UNITED STATES PATENT OFFICE.

EDGAR R. HAWLEY, OF SALT LAKE CITY, UTAH.

VACUUM-OPERATED LIQUID-FUEL-FEEDING DEVICE.

1,216,992.

Specification of Letters Patent.

Patented Feb. 20, 1917.

Application filed February 25, 1916. Serial No. 80,551.

To all whom it may concern:

Be it known that I, EDGAR R. HAWLEY, a citizen of the United States, and a resident of Salt Lake City, in the county of Salt Lake and State of Utah, have invented a new and Improved Vacuum-Operated Liquid-Fuel-Feeding Device, of which the following is a full, clear, and exact description.

10 My invention relates to a means for feeding liquid fuel to an internal combustion engine, and particularly to a feeding device for the indicated purpose, the operation of which is controlled by the suction produced 15 by the engine when in operation.

The objects and advantages of my improved feeding device will appear as the description proceeds.

Generally speaking, an object of the invention is to provide a feeding device as characterized, improved in various particulars with a view to insure reliability of operation as well as to provide for accuracy of adjustment and control.

25 Reference is to be had to the accompanying drawings forming a part of this specification in which similar reference characters indicate corresponding parts in all of the views.

30 Figure 1 is a vertical section of a feeding device embodying my invention;

Fig. 2 is a horizontal section on the line 2-2, Fig. 1;

Fig. 3 is a side elevation of the feeding device, showing the same in position for use in connection with a fuel supply, a carbureter, and an internal combustion engine, represented diagrammatically.

35 My improved feeding device includes a shell or casing designated generally by the numeral 10, from the upper portion of which a suction pipe 11 leads. The pipe 11 may be variously connected with a carbureter, intake manifold or engine to be subject to the suction of the latter, but I prefer to connect the said pipe 11 with a carbureter 13 at a point 12 that will cause the air from the pipe 11 to be drawn past the carbureter nozzle to thereby take up its proportion of 40 fuel and thus not interfere with the functions of the carbureter. The carbureter, as conventionally shown, is connected with the manifold 14 of an engine 15, as usual.

The numeral 16 designates a fuel supply 45 which is under atmospheric pressure and

communicates with the interior of the casing 10 at the top through a pipe 17 and any suitable connection 18.

The numeral 19 designates an outlet pipe from the bottom of the casing 10, leading to 60 the float chamber 20 of the carbureter.

Communication between the pipe 11 and the casing 10 is established by any suitable connection 21 and a chamber 22 having a port 23 leading to the interior of said casing 65 at the top. Said port 23 is regulated by a screw valve 24.

The feed device is divided horizontally into chambers, there being an upper fuel-receiving chamber 25, within which is 70 erected a cup 26, having a float 27 therein. A horizontal partition 28 separates the receiving chamber 25 from a second fuel chamber 29, beneath said first chamber. The fuel chamber 29 contains a float 30 having a 75 valve 31 at the top movable with the float to and from a seat 32^a to control a vertical passage 32 formed in the partition 28, and communicating with the chambers 25, 29.

Below the fuel chamber 29 is a third 80 chamber 33, constituting a reservoir, from which the fuel is drawn, as required by the carbureter, through the pipe 19. The reservoir 33 may be formed by a separate shell section 10^a. The pipe 19 communicates with 85 the reservoir 33 through any suitable connection 34. A drain cock 35 may be provided for the reservoir 33.

An opening 36 leads through the horizontal partition 37, separating the chamber 29 90 from the reservoir 33, and said opening is commanded by a pivoted valve 38 having a counterbalance arm 39.

The reservoir 33 is vented through a port 40 and a pipe 41 communicating therewith 95 and having its outlet end 42 above the chamber 25.

The fuel from the pipe 17 passes into the feed device 10 from the connection 18 through a screen 43, and a port 44 formed in 100 a screw plug 45, said port being controlled by a reciprocating valve 46. The port 44 leads to a pipe 47 that extends downwardly in the chamber 25 into the space 48 outside of the cup 26. The chamber 25, in addition 105 to communicating with the next lower fuel chamber 29, through the cup 26 and passage 32, communicates also with said chamber 29 through the space 48 and a vertical passage 49 in the partition 28 at said space. 110

A stem 50 on the float 27 is provided at its upper end with a valve 51 which, when the float is in the lower position, is seated on a seat 52 at the upper end of an air inlet 53 at the top of the casing 10. A removable cap 54 is provided on the casing 10 above the valve 51 to permit of grinding the said valve without opening the casing. To permit a relative rocking of the float 27, without affecting the valve 51, the stem 50 is loosely connected to said float, there being a head 56 on the stem received in a box 57 on the float, said stem extending through the screw cap 58 of the box.

15 The suction produced in the pipe 11 by the operation of the engine will result in producing a partial vacuum in the feed device 10 and the forming of the vacuum will result in closing the valve 38. Fuel entering from the supply pipe 17 will pass through the port 44 and pipe 47 into the space 48 of chamber 25 and through the passage 49 into the fuel chamber 29. As the fuel accumulates in the chamber 29, the 20 float 30 will rise and close the passage 32. The continued flow of the fuel from the pipe 47 will cause the same to rise through the passage 49 and accumulate in the space 48 of chamber 25 until finally the fuel overflows in the cup 26, thereby causing the float 25 30 to rise and thereby lifting the valve 51 from its seat and permitting air to flow through the inlet 53, thus breaking the vacuum caused by suction in the pipe 11. The 35 restoring of the atmospheric pressure in the several chambers results in the valve 38 opening, and the fuel in the chamber 29 and the space 48 of chamber 25 will run by gravity into the reservoir 33. When the 40 fuel from the reservoir 33 is consumed by the carburetor to an extent to permit the float 30 to fall, the passage 32 will be opened and the fuel from the cup 26 will flow downwardly to chamber 29 and reservoir 33 until 45 the float 27 falls and brings the valve 51 to its seat 52, thereby closing the air inlet 53, whereupon the suction in the pipe 11 will cause the operation to be repeated. It is to be observed that there is open and constant 50 communication between the suction pipe 11 and the interior of the feed device, whether the valve 51 is open or closed. Thus, the operation of the feed device is insured without providing any means to make and break the communication between the suction pipe 55 and the feed device, thereby simplifying the construction. The only control of the suction is through the adjustment of the screw valve 24 to vary the port 23 and thus vary the period of operation as may be required.

The described operation presupposes a fuel supply at 16 below the level of the inlet port 44. In order to insure a positive cut off of the fuel from the supply 16, when the latter is at a higher level than the port 44, I

provide on the valve stem 50, trips 59, 60, which are disposed above and below an arm 61 of a bellcrank lever, the other arm of said lever being in engagement with the stem 62, of the valve 46 controlling the passage 44. Thus, when the valve 51 is raised and fuel is flowing into the feed device, should the level of the fuel continue to rise in the chamber 25, the continued movement of the float 27 will cause the trip 59 to engage the bellcrank 61 and positively close the valve 46, thereby cutting off the fuel. Upon a downward movement of the float 27, the upper trip 60 will engage the bellcrank lever 61 and open the valve 46. The provision of the means to positively close the valve 46, prevents a possible overflow of the fuel in the port 23 and air passage 53, should the fuel continue to rise in the chamber 25 from any cause other than that of a fuel supply above the port 44.

The level at which the fuel supply will be cut off by the valve 46 may be varied by adjusting the screw plug 45 to or from the said valve 46.

Referring again to the float 30 and valve 31, I would explain that it is important to keep the air valve 51 open some little time to maintain the vacuum broken and thus allow the accumulated liquid in the chamber 48 and cup or float chamber 26 to run into the reservoir below, and the float 30 and valve 31; it is to be understood, is given as an example of one means for delaying the outflow of the fuel from the float chamber 26 and thus maintaining the float 27 raised. It is to be observed also, that the port 53 is considerably larger than the port 23 and that the valve 51 has considerable area so that when a vacuum is produced within the device, the pressure upon the valve 51 at the under side is less than the atmospheric pressure acting on the upper side of the valve, the area of the valve 51 being appreciable relatively to the size of the float 27; a result is that the float 27 is held down until the liquid rises higher around said float than would be required to float the same if the difference of pressure did not exist on the valve 51. With this arrangement, when the valve 51 finally opens, it is suddenly raised to a considerable distance as the pressure within and without is the same and the accumulated gasoline in the float chamber 26 raises the said valve high off its seat in raising the float 27.

The described construction affords a practical means for carrying my invention into effect and I will state in conclusion that I do not limit myself to the mechanical details herein illustrated since manifestly the same can be considerably varied without departure from the spirit of the invention, as defined in the appended claims.

Having thus described my invention I

claim as new and desire to secure by Letters Patent:

1. An apparatus of the class described including a reservoir, in the bottom thereof, a fuel-receiving chamber at the top of the feeding device, a second fuel-receiving chamber beneath the first chamber between the same and the reservoir, there being an opening from the upper chamber to the intermediate chamber and an opening from the intermediate chamber to the reservoir, means to connect the reservoir with a carbureter to deliver fuel to the latter, means to connect the upper receiving chamber with a fuel supply, said upper chamber having an air inlet, continuously acting suction-producing means communicating with the upper chamber and tending to produce a vacuum in the feeding device, a valve controlling the opening between the intermediate chamber and the reservoir and subject to a vacuum in the feeding device, a float-operated valve in the intermediate chamber controlling the opening leading to said chamber from the upper chamber, a float in the upper chamber, and a valve operated by said float and controlling the said air inlet.

2. An apparatus of the class described including a reservoir, means to connect said reservoir with a carbureter to deliver fuel to the latter, a fuel-receiving float chamber above the reservoir, a fuel-receiving float chamber above the first chamber, said feeding device having a fuel inlet, the first chamber having an opening for the flow thereto of fuel, the said chambers communicating so that fuel after filling the first receiving chamber will rise in the float chamber above, continuously acting means tending to draw in the fuel from the said supply; means to intermittently cause the cessation of the fuel delivery, a float in the upper chamber controlling said last-mentioned means, a float in the second chamber, and a valve controlled by said second float and controlling communication from the upper float chamber to the said first chamber.

3. An apparatus of the class described including a reservoir, means to connect the reservoir with a carbureter to deliver fuel to the latter, a fuel-receiving chamber above the reservoir and having an outlet in the bottom thereof, means to establish communication between the said outlet and the reservoir, a fuel-receiving float chamber in said first chamber, a float in the float chamber, means to produce a vacuum in the said chambers, an air inlet leading to the first chamber, a valve controlling said air inlet and operated by the rising and falling of the float to admit air and break the vacuum

for permitting fuel to flow to the reservoir, and means independent of the outlet in the bottom of the first chamber to discharge the fuel from the float chamber and permit the float to fall after the level of the fuel has lowered in the first-mentioned chamber.

4. An apparatus of the class described including a reservoir, means to connect said reservoir with a carbureter to deliver fuel to the latter, a fuel-receiving chamber above the reservoir, the bottom of the said chamber having an outlet, means to establish communication between said outlet and the reservoir, a float chamber within the first mentioned chamber and in communication with said chamber at a point considerably above the bottom of the float chamber, the bottom of the said float chamber having an outlet means to establish communication between the last-mentioned outlet and the reservoir, means controlling the outlet of fuel from the float chamber and adapted to hold the fuel in the float chamber until the fuel has lowered in the first chamber, suction-producing means to create a vacuum in the said chambers, an air inlet, a float in the float chamber, and a valve operated by the said float and controlling said air inlet.

5. An apparatus of the class described, including a reservoir subject interiorly to atmospheric pressure, means to connect said reservoir with a carbureter to deliver fuel to the latter, a fuel-receiving float chamber above the reservoir, a fuel-receiving cup above the said chamber, a fuel-supply means delivering to said feeding device, the said chamber having an opening for the flow thereto of fuel delivered from said supply, the said chamber and cup communicating so that fuel after filling the said first chamber will rise and overflow into the said cup at the top, means for retaining the liquid in the said cup until the liquid surrounding the cup and in said chamber has been drawn off to a certain level, means for allowing the liquid to flow from the said cup, continuously acting means tending to draw the fuel from said supply, valve means to intermittently cut off the fuel delivery, a float in the said cup attached to and controlling the said valve means, a float in the said chamber and a valve controlled by the last mentioned float, said valve controlling outlet from the cup to said chamber.

In testimony whereof I have signed my name to this specification in the presence of two subscribing witnesses.

EDGAR R. HAWLEY.
